UNITED STATES PATENT OFFICE.

GUY H. PROCTOR, OF SOMERVILLE, MASSACHUSETTS, ASSIGNOR TO NEW ENGLAND ELECTRIC MANUFACTURING COMPANY, OF BOSTON, MASSACHUSETTS, A CORPORATION OF MASSACHUSETTS.

INCANDESCENT-LAMP SOCKET.

SPECIFICATION forming part of Letters Patent No. 745,294, dated November 24, 1903.

Application filed September 16, 1902. Serial No. 123,420. (No model.)

To all whom it may concern:

Be it known that I, GUY H. PROCTOR, a citizen of the United States, residing at Somerville, in the county of Middlesex and State of Massachusetts, have invented new and useful Improvements in Incandescent-Lamp Sockets, of which the following is a specification.

This invention relates to sockets for incandescent lamps, the object of the invention being to provide a simple and practical lamp-socket the different parts of which may be quickly and easily removed and fastened together.

The invention consists in the combination in an incandescent-lamp socket of a supporting-block formed of a single piece of insulating material provided with two transverse passages and a longitudinal passage connecting said transverse passages, said transverse 15 passages having a common longitudinal median plane and separated one from the other by a portion of said block extending therebetween, a circuit-controlling key and a bearing-plate therefor located in one of said transverse 20 passages and a key-controlling spring located in the other of said passages.

The invention further consists in the combination and arrangement of parts set forth in the following specification and particularly 25 pointed out in the claims thereof.

Referring to the drawings, Figure 1 is a top plan view of my improved lamp-socket with the key in position to break the circuit. Fig. 2 is a front elevation of the same. Fig. 3 is 30 a view similar to Fig. 2, showing the circuit-controlling key turned at right angles to the position shown in Fig. 2 and completing the circuit. Fig. 4 is an underneath plan of the same. Fig. 5 is a side elevation viewed from 35 the left of Fig. 3. Fig. 6 is a vertical longitudinal section taken on line 6 6 of Fig. 3. Fig. 7 is a vertical transverse section taken on line 7 7 of Fig. 1. Fig. 8 is a vertical transverse section taken on line 8 8 of Fig. 1. Fig. 9 is a perspective view of the circuit-controlling key, together with the bearing-plate upon 40 which the shaft of said key is arranged to rotate. Fig. 10 is a perspective view of the key-controlling spring. Fig. 11 is a detail front 45 elevation of the insulating supporting-block. Fig. 12 is a vertical longitudinal section taken on line 12 12 of Fig. 11. Fig. 13 is a perspective view of the central contact-plate. Fig. 14 is a vertical central section similar to Fig. 6, illustrating a modified means for attaching 50 the lamp to the socket.

Like numerals refer to like parts throughout the several views of the drawings.

In the drawings, 15 is a supporting-block formed of insulating material. Said supporting-block is provided with two transverse passages 16 and 17, each of said passages extending across and opening through one end of said block. The block 15 is also provided with a longitudinal passage 14, connecting 60 said transverse passages and opening through the periphery of said insulating-block, said passages being for the reception of certain parts, as hereinafter set forth.

The circuit-controlling key 18 consists of a 65 shaft 19, having a handle 20 fast to one end thereof and a rotary contact-block 21 loosely mounted upon the opposite end thereof in a manner well known to those skilled in the art, with a lost motion between said block and 70 shaft. The shaft 19 is rotatably mounted in bearings 22, provided upon a bearing-plate 23. The bearing-plate 23 has an arm 24 thereon, which is provided with a binding-screw 25, by means of which one of the wires 27 is 75 attached to said bearing-plate. The arm 24 is located in a recess 26, provided in and extending part way around the periphery of the supporting-block 15, and the circuit-wire 27 passes through a recess 28, extending from the 80 recess 26 upwardly to the end of the block 15.

A flat spring 29 is located in the upper transverse passage 16, one end thereof bearing against the rotary contact-block 21 and the other end thereof being provided with ears 90 30, through which screws 31 31 extend, said screws passing through an insulating-plate 32, located above the spring 29, thence through the ears 30 upon the flat spring 29, downwardly through holes provided in the supporting-block 15 and having screw-threaded engagement with ears 33, provided upon the bearing-plate 23. It will thus be seen that the circuit-controlling key, the bearing-plate 95 in which it is rotatably mounted, the bind- 100

ing-screw 25, the spring 29, and the insulating-plate 32 are all fastened to the insulating-block 15 by the two screws 31 31.

The screw-threaded shell 34, into which the 5 incandescent lamp (not shown) is screwed, is attached to the supporting-block 15 by two screws 35 35, which pass downwardly through the insulating supporting-block 15, Fig. 8, and have at their lower ends screw-threaded en- 10 gagement with an annular contact-ring 36. Said ring 36 and screws 35 clamp the shell 34 against an insulating-washer 37, said insulating-washer being in turn clamped against the bottom of the supporting-block 15. The con- 15 tact-ring 36 is provided with an upwardly-ex- tending arm 38, upon which is provided a binding-screw 39, by means of which the second circuit-wire 40 is attached to said arm. Said circuit-wire extends upwardly in a re- 20 cess 41, provided in the periphery of the sup- porting-block 15 and extending longitudinally from top to bottom thereof.

A central contact-plate 42 is clamped by the insulating-washer 37 against the bottom 25 of the block 15 and consists of two horizontal arms 43 and 44, the arm 43 being arranged to bear against one end of the rotary block 21 when the circuit is completed, as in Fig. 6, and the other arm 44 being arranged to bear 30 against the central contact-terminal of the lamp. It will be noted that the arm 43 projects into the transverse passage 17, and being clamped therein, as hereinbefore de- 35 scribed, the central contact-plate 42 is held securely in position. The two arms 43 and 44 are connected by a vertical portion 45, which extends through a slot 46, provided in the insulating-washer 37.

When an incandescent electric lamp is 40 screwed into the threaded shell 34 and the circuit-controlling key is turned to the position shown in Figs. 3 and 6, the current passes from the wire 27 through the key-shaft 19 and rotary contact-block 21 to the upper arm 43 45 of the central contact-plate 42, thence through the lower arm 44 to the central contact-plate terminal of the lamp, passing through said lamp and from the outer terminal thereof to the annular contact-ring 36, thence through 50 the arm 38 to the second circuit-wire 40. The circuit is broken by turning the key from the position shown in Figs. 3 and 6 to that shown in Figs. 1 and 4.

In Fig. 14 I have illustrated a modified form 55 of socket adapted to have attached thereto a Thomson Houston incandescent lamp with a screw-thread provided in the center instead

of upon the exterior of the upper end of the lamp. In this modified form of socket the shell 34 is removed and a screw-threaded pro- 60 jection 47 is provided upon the arm 44 of the central contact-plate 42.

Having thus described my invention, what I claim, and desire by Letters Patent to se- 65 cure, is—

1. In an incandescent-lamp socket, a sup- 70 porting-block formed of a single piece of in- 75 sulating material provided with two trans- 80 verse passages and a longitudinal passage connecting said transverse passages, said transverse passages having a common longi- 85 tudinal median plane and separated one from the other by a portion of said block extend- 90 ing therebetween, a circuit-controlling key and a bearing-plate therefor located in one of 95 said transverse passages, and a key-control- 100 ling spring located in the other of said pas- sages.

2. In an incandescent-lamp socket, a sup- 105 porting-block formed of a single piece of in- 110 sulating material provided with two trans- 115 verse passages and a longitudinal passage connecting said transverse passages, said transverse passages having a common longi- 120 tudinal median plane and separated one from the other by a portion of said block extend- 125 ing therebetween, each of said passages ex- 130 tends across and opening through its re- 135 spective end of said supporting-block, a cir- 140 cuit-controlling key and a bearing-plate there- 145 for located in one of said transverse passages, and a key-controlling spring located in the other of said passages.

3. In an incandescent-lamp socket, a sup- 150 porting-block formed of a single piece of in- 155 sulating material provided with two trans- 160 verse passages and a longitudinal passage connecting said transverse passages, said transverse passages having a common longi- 165 tudinal median plane and separated one from the other by a portion of said block extend- 170 ing therebetween, each of said transverse 175 passages extending across and opening through its respective end of said supporting-block, said longitudinal passage opening 180 through the periphery of said insulating- 185 block.

In testimony whereof I have hereunto set my hand in presence of two subscribing wit- 190 nesses.

GUY H. PROCTOR.
